(57) **CLAIM**

The ornamental design for a spark arrestor, as shown and described.

DESCRIPTION

FIG. 1 is a front perspective view of a first embodiment of a spark arrestor showing my new design;
FIG. 2 is a rear perspective view thereof;
FIG. 3 is a side view thereof;
FIG. 4 is a top plan view thereof;
FIG. 5 is a front perspective view of a second embodiment of a spark arrestor;
FIG. 6 is a rear perspective view thereof;
FIG. 7 is a side view thereof;
FIG. 8 is a top plan view thereof;
FIG. 9 is a front perspective view of a third embodiment of a spark arrestor;
FIG. 10 is a rear perspective view thereof;
FIG. 11 is side view thereof;
FIG. 12 is a top plan view thereof;
FIG. 13 is a front perspective view of a fourth embodiment of a spark arrestor;
FIG. 14 is a rear perspective view thereof;
FIG. 15 is side view thereof;
FIG. 16 is a top plan view of the first embodiment of the design of a spark arrestor;
FIG. 17 is a front perspective view of a fifth embodiment of a spark arrestor;
FIG. 18 is a rear perspective view thereof;
FIG. 19 is a side view thereof;
FIG. 20 is a top plan view thereof;
FIG. 21 is a front perspective view of a sixth embodiment of the design of a spark arrestor;
FIG. 22 is a rear perspective view thereof;
FIG. 23 is a side view thereof; and,
FIG. 24 is a top plan view thereof.
